UNITED STATES PATENT OFFICE.

JOSEPH HIGGINSON AND HUBERT ARUNDEL, OF STOCKPORT, ENGLAND.

LIQUID-FUEL-SUPPLY APPARATUS FOR INTERNAL-COMBUSTION ENGINES.

1,306,762.

Specification of Letters Patent. Patented June 17, 1919.

Application filed December 26, 1917. Serial No. 209,010.

To all whom it may concern:

Be it known that we, JOSEPH HIGGINSON and HUBERT ARUNDEL, subjects of the King of Great Britain and Ireland, and residents 5 of Sovereign Works, Stockport, in the county of Chester, England, have invented certain new and useful Improvements in Liquid-Fuel-Supply Apparatus for Internal-Combustion Engines, of which the following is a specification.

This invention relates to liquid fuel supply apparatus of internal combustion engines of the type in which the fuel is drawn by suction to an intermediate vessel from 15 which it passes to the engine carburetor through a supplementary container or reservoir.

The object of our present invention is to provide simple and convenient means for 20 greatly increasing the quantity of fuel which the intermediate vessel can deal with in a given time, without increasing the size of the vessel.

The invention comprises the improved 25 combinations and arrangements of parts hereinafter described and claimed.

Referring to the accompanying sheets of explanatory drawings:—

Figure 1 is a sectional elevation showing 30 the liquid fuel supply apparatus constructed and arranged in one convenient form in accordance with our invention.

Fig. 2 is a view drawn to a small scale illustrating the connection of the apparatus 35 shown in Fig. 1 with the main fuel supply tank or vessel.

Figs. 3 and 4 show two modifications to be hereinafter described.

Fig. 5 is a sectional elevation showing a 40 modified arrangement of the apparatus.

Fig. 6 shows a modified arrangement of the control valve.

Fig. 7 is a view showing another modified 45 arrangement of the apparatus.

Fig. 8 is a plan view of the intermediate vessel shown in Fig. 7.

The same reference letters in the different views indicate the same or similar parts.

In the application of our invention illustrated in Figs. 1 and 2, the intermediate vessel *a* is of known form having combined therewith a supplementary chamber or vessel *b* disposed around and beneath it, the communicating passage *c* between the two 55 vessels having a flap or other non-return

valve *d* thereon. The suction connection *e* of the intermediate vessel is controlled by a float actuated valve *f*. There is also a pressure connection *g* to the intermediate vessel, the pressure being derived from the pump *h* 60 which also causes the suction or reduced pressure in the suction connection *e*. The float *i* may also control the pressure connection *g* through a valve *j* of any convenient type, the suction connection being opened 65 when the pressure connection is closed and vice versa. If desired, we may provide a valve in the fuel inlet connection to the intermediate vessel also controlled from the float aforesaid but we prefer to employ a 70 simple ball or non-return valve *m* (see Fig. 2) in said connection. The main low level tank is shown at *n* (Fig. 2). It will be seen that for each complete back and forth movement of the piston *t*, the vessel *a* is, if the 75 float *i* allows, subjected first to a reduced pressure and then to a pressure greater than atmospheric.

To maintain a steady pressure in the supplementary vessel *b*, independent of the 80 pressure variations in the intermediate vessel *a*, we provide an atmospheric connection *o* to said vessel and also an overflow passage *p* so that any fuel in excess of requirements forced into said vessel *b* by the pressure 85 which acts in the intermediate vessel *a* will be returned to the main fuel supply tank *n*. The atmospheric connection *o* of the supplementary vessel *b* may be continuously open as in Fig. 1; or it may be closed by a float 90 operated valve *q* (see Fig. 4), when the overflow passage *p* (Fig. 1) will not be required.

Or, we may as shown in Fig. 3 provide a pressure connection *o'* extending between the compressed air passage *g* of the intermediate vessel *a* and the supplementary vessel. The fuel in the latter vessel is then forced therefrom by pressure. An overflow passage as *p* (Fig. 1) is not required with the Fig. 3 arrangement.

If a pump as *h* (Fig. 1) be used as the source of suction and pressure for the intermediate vessel, we provide a relief valve *r* or a small leak aperture in the pressure connection and we arrange air ports *s* in the suction pump cylinder which are uncovered by the piston *t* at the end of its suction stroke so as to destroy the vacuum in the cylinder at each revolution. The piston *t* therefore creates a vacuum in the pipe *e* through the 110

light disk type non-return valve *u* on its suction stroke and creates a pressure in the pipe *g* through a similar valve *v* on its delivery stroke.

- 5 In some cases, instead of positively timing the periods of pressure and suction by the pump piston, we may provide positively operated and timed valves in the suction and pressure connections, the one valve being 10 opened when the other is closed. In one convenient arrangement, as illustrated in Fig. 5, we employ a continuously rotating plug cock *w* controlling four ports, two *x*, *y* from the pump cylinder *h* and one *z*, leading 15 to the float controlled inlet *e* of the intermediate vessel, such inlet serving for both the suction and pressure required in said vessel. The fourth port 2 is an atmospheric connection. The latter may be dispensed 20 with and three ports only be employed as in Fig. 6. The plug cock *w* is rotated from the pump crank shaft by the differential gears shown which impart a slow but continuous rotary movement to the plug. In Fig. 5, the 25 latter is shown in its correct position and is also drawn to an enlarged scale with dotted line connections to the pump and vessel *a*.

With the control cock shown in Fig. 6, the cycle of operations is as follows (1) Suction in vessel *a* (2) Pressure in vessel *a* (3) Idle period but with a slight pressure available for forcing further fuel out of the vessel *a*.

Instead of arranging the supplementary vessel *b* around and beneath the intermediate vessel *a*, we may arrange it at a higher level than the intermediate vessel (as shown in Fig. 7) and provide the non-return valve *d* on the connection *c* between the two vessels. 40 The pressure in the intermediate vessel *a* forces the fuel to the higher tank *b* and it falls therefrom by gravity to the carbureter. The fuel is thus raised from the main supply tank *n* in two stages. The vessel *b* has 45 an overflow pipe *p*. The three way cock as in Fig. 6 may be employed in the Fig. 7 arrangement.

With the arrangements aforesaid in which an overflow pipe *p* is employed, the intermediate vessel *a* is maintained in continuous operation as the pressure conditions therein expel the fuel therefrom to the supplementary vessel *b* (from which any excess fuel returns to the main tank *n*) so that the intermediate vessel is rapidly emptied and in consequence re-filled very frequently. By the employment of our invention, we are enabled to employ very small vessels to give any desired output, so reducing the wind resistance 50 of same when fitted in aeroplanes, or other exposed moving machines.

We may vary the details of our improved apparatus to suit requirements.

Having now described our invention, what we claim as new and desire to secure by Letters Patent is:—

1. In liquid fuel supply apparatus for internal combustion engines, in combination, an intermediate vessel, a supplementary vessel receiving the fuel from the intermediate vessel, a non-return valve on the connection between said vessels, positively operated means placing said intermediate vessel alternately under suction and pressure, a conduit between said means and the intermediate vessel allowing the continuous flow of air therethrough in both directions, and a float valve for cutting off the suction and pressure from the intermediate vessel independently of the positively operated means, as set forth.

2. In liquid fuel supply apparatus for internal combustion engines, an intermediate vessel, a supplementary vessel receiving the fuel from the intermediate vessel, a non-return valve on the connection between said vessels, positively operated means placing said intermediate vessel alternately under suction and pressure, a conduit between said positively operated means and the intermediate vessel allowing the continuous flow of air therethrough in both directions, and a float valve for cutting off the suction and pressure from the intermediate vessel independently of the positively operated means, as set forth.

3. In liquid fuel supply apparatus for internal combustion engines, in combination, an intermediate vessel, a supplementary vessel receiving the fuel from the intermediate vessel, a non-return valve on the connection between said vessels, a rotating plug cock placing said intermediate vessel alternately in communication with a source of pressure and a source of suction, a conduit between said cock and the intermediate vessel allowing the continuous flow of air therethrough in both directions, and a float valve for cutting off the suction and pressure from the intermediate vessel independently of the positively operated means, as set forth.

In testimony whereof we have signed our names to this specification in the presence of two subscribing witnesses.

JOSEPH HIGGINSON.
HUBERT ARUNDEL.
